Term of patent 14 years

(Cl. D7—7)

FIG. 2

FIG. 3

FIG. 1 is a front elevation of a cowboy boot showing my new design;

FIG. 2 is a side elevation;

FIG. 3 is a rear elevation; and

FIG. 4 is a side elevation.

The essential features of my design reside in the ornamental stitching shown on the top of the boot, portions of the design which are conventional being depicted in broken dash-dot lines.

I claim:

The ornamental design for a cowboy boot, as shown and described.
